UNITED STATES PATENT OFFICE.

RICHARD ALLEN REW, OF POMEROY, WASHINGTON TERRITORY, ASSIGNOR TO HIMSELF, CHARLES B. FOOTE, AND JAMES W. HULL, ALL OF SAME PLACE.

HEATING AND VENTILATING APPARATUS.

SPECIFICATION forming part of Letters Patent No. 357,411, dated February 8, 1887.

Application filed May 27, 1885. Serial No. 166,872. (No model.)

To all whom it may concern:

Be it known that I, RICHARD ALLEN REW, a citizen of the United States, residing at Pomeroy, in the county of Garfield, Washington Territory, have invented a new and useful Improvement in Heating and Ventilating Apparatus, of which the following is a description.

This invention relates to that class of apparatus designed for heating and ventilating dwellings and other houses; and its object is to provide the heater with plenty of pure air, to economize fuel by extracting as much heat as possible from the products of combustion, to properly temper the heated air by discharging steam into it in any desired quantity, to draw foul air from the room, and to admit pure air.

To this end my invention consists in the construction and combination of parts forming the heating and ventilating apparatus hereinafter described and claimed, reference being had to the accompanying drawings, in which—

Figure 1 is a central vertical section of a portion of a room, showing my invention. Fig. 2 is a plan view of the heater. Fig. 3 is a horizontal section of the same at x. Fig. 4 is a detail perspective view illustrating the steam-pipe shield. Fig. 5 is an enlarged longitudinal section of my apparatus.

A represents the outer shell or body of a stove, mounted on legs a upon the floor C of a room, one of whose side walls is represented at C'.

B is the combustion-chamber, in which fuel of any suitable kind may be burned. b is the ash-pit.

D is the inner lining of the stove, having a perforated top, D'.

E represents a hot-air chamber, of which E' is the bottom, corresponding in form and perforations with the top D', and connected therewith by a series of pipes, d, through which the products of combustion pass from the chamber B. A pipe may connect the chamber E directly with the chimney-flue; but I prefer to interpose another chamber, F, having its bottom F' perforated to receive a series of small flues or pipes, f, which communicate with the chamber E.

G represents a heat-deflector in the form of a plate or sheet of metal interposed between the head D' and the bottom E'.

H is a lining intermediate between the drum A of the stove and the inner lining, D, and it parts the space into two annular air-passages, h and h'. The passage h receives air from the pipe Q, which opens into the cold-air chamber, and the latter communicates with the passage h', which carries the cold air upward around the combustion-chamber, which heats it to some extent, to the first deflector, G, which forces it to pass between the pipes d, from which it receives more heat. Then it passes through the central opening in the plate G and spreads outward again, passing between the pipes d, between the deflector and the bottom of the chamber E, thence upward beside this chamber to the upper deflector, G, which turns it inward, and again outward between pipes f, to rise around the chamber F, whence it may escape directly into the room through apertures K near the circumference of the stove; or when these apertures are closed by a suitable damper, K', the heat will be forced to the center of the top of the stove to escape at L, where there is a damper to prevent the too sudden or rapid escape of heat. When both dampers K' and L are closed, the heat is forced to descend between the shell A and the intermediate lining, H, to find exit at the apertures H'.

I' is an ornamental cover for the top of the stove.

M is a tank at the side of or behind the stove to contain water. It is intentionally located away from the heat in order to avoid too rapid evaporation, and it is located beside or behind the stove, that it may be large enough to be of real service without being in the way or so unsightly as it would be if located on top of the stove.

N is a pipe entering the tank near the bottom thereof and passing across through the stove between the heating-pipes d, and slightly ascending toward the outer end of the pipe, in order that the bubbles of steam may pass from said outer end rather than into the tank. At the point N' the steam-pipe bends to a vertical position and rises to the level N² of the

top of the tank, where it is bent downward and returns as far as the center N^3 of the hot-air chamber, making a bend near N' .

O is a shield of semi-cylindrical form adapted to rest directly on top of the steam-pipe, or to be turned around the pipe downward, so as to partially or wholly shield the under side of the pipe from heat. The shield O is shown most clearly in Fig. 4. By this means the amount of steam found to be discharged into the heated air may be regulated to temper the air at will. The vertical portion from N' to N^2 of the pipe is necessary to prevent the water from running directly out of the tank.

15. A trap-shaped pipe, m , is employed for feeding air to the combustion-chamber. This pipe may, by preference, be arranged as shown in Fig. 1, where its upper end extends into the fire-box and its lower end extends close to the floor, whereas a somewhat different construction is shown in Fig. 5, in which case the pipe is detachably connected with a chamber which communicates with the combustion-chamber by an opening covered by a screen, as will be 25 clearly understood from the said figure of the drawings. The trap-shaped curves are to prevent ashes or coals of fire from falling through the tube and the tube, is removable for cleaning purposes. The inside lining, D , is formed 30 with a bottom separated from the bottom of the stove A , forming a cold-air chamber, P , beneath the ash-pit. This chamber is provided with air by a pipe, Q , which, passing beneath the floor C of the room, communicates with 35 outdoor air.

A pipe, Q' , may be arranged vertically in the wall of the room, and I provide this pipe with a damper-valve, W , and have its lower end communicating with the room by an opening formed through the mop-board, whereby 40 impure air may be discharged from the room.

The stove may be of any desired form.

The smoke-chamber F is a mere repetition of the chamber E , and any number of such 45 repetitions may be made to extract more and more of the heat from the products of combustion and disseminate it through the medium of pure air passing between the flues and deflectors.

50. I do not in this application claim, broadly, the trap-shaped pipe for supplying air to the combustion-chamber; but I reserve the right to claim such pipe, broadly, and, if desired, in connection with the particular construction 55 whereby it is connected with the combustion-chamber, substantially as herein shown in Fig. 5, in a separate application for patent filed by me on or about November 23, 1886, Serial No. 219,701.

60. What I claim as my invention, and desire to secure by Letters Patent, is—

1. The combination, with a stove having an air-inlet and a smoke-outlet, of the outer wall or casing having an outlet at its lower end, the 65 top and bottom, the combustion and smoke chambers, tubular connections extending be-

tween said chambers and opening at their opposite ends into the same, and an intermediate lining between the said chambers and the outer wall or casing, substantially as set forth. 70

2. In a stove, the combination of the outer and inner cylinders having an intermediate air-space, the combustion and smoke chambers located within the inner cylinder, pipes connecting and opening at their ends into said chambers, and a deflector-plate extended transversely between the walls of the inner cylinder, and located between the two said chambers and having a central opening, substantially as set forth. 75

3. The combination of the combustion-chamber having a closed or imperforate bottom, a casing inclosing said chamber and extending below and forming an air-chamber below the combustion-chamber, and a pipe extended 85 through the casing and opening within the combustion-chamber, whereby air may be admitted to said chamber, substantially as set forth.

4. The combination, with the casing and 90 the combustion-chamber inclosed within the same, of a pipe extended through the casing into and opening at its inner end within the combustion-chamber, and having its lower end extended downward and opening without the 95 casing, such pipe being formed with a trap, substantially as set forth.

5. In a stove, the combination of the casing, a combustion-chamber and hot-air space within 100 said casing, a water-tank, and a pipe extended therefrom, and having a discharge within the hot-air space and adjacent the combustion-chamber, substantially as set forth.

6. The combination, with the combustion-chamber, the casing, and the water-tank having 105 a pipe extended adjacent to the combustion-chamber, of a shield and supports therefor, whereby it may be set between the combustion-chamber and the said pipe, substantially as set forth. 110

7. In a stove, the combination of the casing, a combustion-chamber and hot-air space arranged within said chamber, a water-tank, and a pipe extended therefrom adjacent to the combustion-chamber, whereby its contents may 115 become heated, and said pipe being extended, forming an upwardly-projected wing, a return-wing, and a discharge portion, the latter opening into the hot-air chamber, substantially as set forth. 120

8. In combination with a stove having a combustion-chamber and a hot-air chamber, a water-tank and a pipe extended therefrom and inclined upward, substantially as described, and provided with an extension-opening adjacent the combustion-chamber, substantially as set forth. 125
